UNITED STATES PATENT OFFICE.

JAMES A. MALONEY, OF WASHINGTON, DISTRICT OF COLUMBIA.

DESIGN FOR A SADDLE-PLATE.

SPECIFICATION forming part of Design No. 26,831, dated March 30, 1897.

Application filed January 28, 1897. Serial No. 621,106. Term of patent 7 years.

To all whom it may concern:

Be it known that I, JAMES A. MALONEY, a citizen of the United States, and a resident of Washington, in the District of Columbia, have 5 invented a certain new and useful Design for a Saddle Plate or Frame; and I do declare the following to be a full, clear, and exact description of the invention, such as will enable others skilled in the art to which it appertains 10 to make and use the same, reference being had to the accompanying drawings, and to letters of reference marked thereon, which form a part of this specification.

Figure 1 of the drawings is a plan view of 15 the invention, and Fig. 2 is a section of same.

This invention has relation to a certain new and original design for saddle plates or frames; and it consists in the novel form and configuration thereof, all as hereinafter described, and 20 illustrated in the accompanying drawings.

The design more particularly consists in a thin plate having parallel upper and lower

plane surfaces, whose front edge is bilaterally concave or formed with opposite symmetrical reentrant curves *a a*, which terminate in and are united by a convex projection *b* at the central portion, whose rear edge forms one side of an ellipse, whose end portions are also approximately elliptical, the curves thereof merging into the reentrant curves *a*, and whose body 25 portion has therein an elongated transverse slot or opening *g* of uniform width throughout its length, its front and rear edges being straight and parallel and its ends *g' g'* concave. 30

Having thus described my invention, what 35 I claim is—

The design for a saddle plate or frame substantially as herein shown and described.

In testimony whereof I affix my signature in presence of two witnesses.

JAMES A. MALONEY.
